UNITED STATES PATENT OFFICE.

ALFRED BERSTED AND MARTIN BERSTED, OF CHICAGO, ILLINOIS.

DESIGN FOR AN ELECTRIC CORN POPPER.

Application filed July 16, 1928. Serial No. 27,506. Term of patent 7 years.

To all whom it may concern:

Be it known that we, ALFRED BERSTED and MARTIN BERSTED, citizens of the United States, residing at 5401-21 West Sixty-fifth Street, Chicago, Cook County, Illinois, have invented a new, original, and ornamental Design for an Electric Corn Popper, of which the following is a specification, reference being had to the accompanying drawings, forming part thereof.

Figure 1 is a top plan view of the electric corn popper.

Figure 2 is a side view of the electric corn popper, showing our new design.

We claim:

The ornamental design for an electric corn popper, as shown.

ALFRED BERSTED.
MARTIN BERSTED.
